UNITED STATES PATENT OFFICE.

EMIL TYDEN, OF HASTINGS, MICHIGAN.

DESIGN FOR A BODY FOR SELF-LOCKING SEALS.

SPECIFICATION forming part of Design No. 32,391, dated March 27, 1900.

Application filed March 2, 1900. Serial No. 7,130. Term of patent 14 years.

To all whom it may concern:

Be it known that I, EMIL TYDEN, a citizen of the United States, residing at and having post-office address at Hastings, county of Barry, State of Michigan, have invented and produced a new and original Design for a Body of a Self-Locking Seal, of which the following is a specification, reference being had to the accompanying drawings forming part

10 thereof.

Figure 1 is a side elevation of the seal body of my said new design. Fig. 2 is an elevation at right angles to the elevation shown in Fig. 1. Fig. 3 is a top or bottom plan, the said seal being identical in appearance at top and bottom or opposite ends.

15 My said design is characterized by the form and arrangement of the three elements of this outline—to wit, the two domes A and B and the prominent boss or bead C. The two domes

are of the same diameter at their bases. One is higher or longer than the other. They are disposed base to base and delimited by the boss or bead C, which encompasses their bases. Each dome has at the top or crest a narrow 25 diametric slot D in length very nearly equal to the full diameter of the base of the dome. These two slots are in the same diametric plane.

I claim—

30 The design for a body for a self-locking seal, herein shown and described.

In testimony whereof I have hereunto set my hand at Hastings, Michigan, in the presence of two witnesses, this 26th day of February, A. D. 1900.

EMIL TYDEN.

In presence of—
NORA COOPER,
A. C. BROWN.
